[57] CLAIM

The ornamental design for a motorcycle fairing, as shown and described.

DESCRIPTION

FIG. 1 is a side elevational view of a motorcycle fairing, showing my new design.

FIG. 2 is a front elevational view.

FIG. 3 is a top plan view.

FIG. 4 is a bottom plan view; and

FIG. 5 is a rear elevational view.

The side elevational view not shown is a mirror image of FIG. 1.
